UNITED STATES PATENT OFFICE

FRANZ G. BACK, OF STAMFORD, CONNECTICUT, ASSIGNOR, BY MESNE ASSIGNMENTS,
TO THE PHOTOR CORPORATION, OF NEW YORK, N. Y., A CORPORATION OF NEW
YORK

ELECTRICAL APPARATUS

Application filed April 18, 1929. Serial No. 356,087.

This invention relates to an improvement in electrical apparatus, and has for one of its objects the provision of an apparatus capable of generating momentarily a difference 5 in potential across two terminals, without the use of moving parts, the apparatus being usable with direct and alternating current interchangeably.

A still further object of my invention is the 10 provision of an electrical apparatus which is capable of use interchangeably with direct and alternating current, involves no moving parts and is capable of stepping up by induction and to the desired degree the current 15 impressed on the apparatus.

More specifically the present invention provides electrical apparatus comprising a core of soft iron provided with an air gap, this core being provided with a primary 20 winding and with a secondary winding, the primary winding to be connected to a power source, which, as above mentioned, may be either direct or alternating current, while the 25 device or apparatus to be energized or excited is connected across the secondary winding.

In the accompanying drawing in which an embodiment of my invention has been illustrated more or less diagrammatically, 1 30 designates a core, which is a built up laminated structure of soft iron having a cross-sectional area of thirty-six square centimeters, for example. This core is of the ring type as distinguished from the bar type and 35 is provided with an air gap 2. With an apparatus having the cross-sectional area above referred to this air gap may be 2 x 3 millimeters.

3 designates a primary winding composed 40 of ninety-six turns of #14 copper wire, while 4 designates a secondary winding composed of one hundred and eighty turns of #14 copper wire. It is to be understood that the above figures are by way of example and 45 may be varied within the scope of this invention.

In an apparatus constructed as above described, and using a power circuit for the primary of 110 volts, I have obtained a potential difference across the secondary of from

400 to 440 volts, employing either direct current or alternating current.

I have illustrated the secondary 4 as being attached to the two electrodes 5 and 6 of a lighting device or lamp, the electrodes 5 and 55 6 being bridged by a highly refractory metal wire 7 such as tungsten.

The lighting device also comprises a glass tube 8, caps 9 and 10 in each end of the tube, the filament or wire 7 within the tube being 60 held in place in the caps 9 and 10 by the electrodes 5 and 6 which as illustrated are tapered and frictionally hold the filament in place. The apparatus is capable of momentary operation only, as distinguished from 65 the operation of an alternating current transformer, for example, and as will be explained hereinafter the filament 7 during this momentary operation is vaporized, this vapor being confined in the tube 8 then carrying the charge across electrodes 5 and 6 to 70 produce a blue or bluish-white glow or flash particularly well adapted for photographic purposes.

The primary winding 3 is adapted to be 75 connected to any power circuit either alternating current or direct current. In one side of the primary I insert a wire 11 which is burned out or destroyed after a predetermined interval of time has elapsed each time 80 the apparatus is operated, and must be replaced. In the primary circuit I also provide resistance 12 which may take the form of a lamp. Across this lamp I provide a manually operable switch 13 adapted when 85 closed to short circuit the lamp.

In operation and assuming first of all that my improved apparatus is connected to a power circuit of 110 volts direct current, and assuming that the lighting device is connected as shown across the secondary circuit, with the manually operable switch 13 open, direct current will flow through the wire 11, lamp 12, primary winding 3 to the other side of the line. The resistance of the lamp 12 is such that the wire 11 under these conditions will not be burned out and substantially no current will be built up in the secondary 4. 90

The switch 13 is then closed, short circuiting the lamp 12, thereby reducing the resist- 95

ance of the primary circuit of the apparatus sufficiently to cause the wire 11 to be burned out in 1/120 of a second, for example, to open the electric circuit of primary winding 3.

- 5 The closing of the switch 13 and short circuiting of the lamp 12 permits sufficient current to pass through the primary winding 3 for a sufficient length of time to cause the core 1 to become magnetically saturated at about 10 14000 lines of force per square centimeter, the electric energy necessary for creating this condition being materially in excess of that required were the air gap eliminated due to the reluctance of air being higher than 15 that of iron. Of course the opening of the circuit of the primary 3 due to the destruction of wire 11 permits of the quick collapse of the magnetic circuit and a current of high voltage due to the high reluctance of the air 20 gap 2 is induced in the secondary 4. This current is sufficient to vaporize the filament 7 and to cause a momentary glow or flash within the tube 8.

In use on an alternating current power circuit the same procedure is followed and the results are the same as in the case of use on a direct current circuit, the circuit of the primary 3 being broken on the half cycle of a 60 cycle alternating current, due to the fact 30 that the wire 11 is destroyed in 1/120 of a second as above explained.

It will be understood from the foregoing that the provision of the air gap 2 in my improved apparatus permits of the dimensions 35 of my apparatus being kept down to the minimum, the air gap increasing the reluctance of the magnetic circuit and hence increasing the energy required for saturating the core and effecting a quick collapse of the 40 magnetic circuit when the primary circuit is opened, a result desired in order that current may rapidly rise in the secondary 4. This result otherwise could not be obtained except by increasing the dimensions of the core beyond practical limits.

It will be understood also that the total magnetic energy produced by the current flowing in the primary winding of the apparatus is stored by the air gap and becomes 50 available for inducing current in the secondary winding upon the opening of the primary circuit, thus enabling either direct current or alternating current to be used in the primary winding.

55 It will be understood, furthermore, from the foregoing that by properly computing the number of turns in the primary with respect to the number of turns in the secondary, and the amount of copper in the primary and 60 secondary as compared with the iron in the core and with due consideration of the air gap any voltage desired can be induced in the secondary.

It is to be understood also that the wire 11 65 in the circuit of the primary 3 and which

has been described as of such a character as to be destroyed in 1/120 of a second, may be varied as to this characteristic, this time interval depending upon the circuit on which it is or with which it is to be used.

The apparatus of this application while capable of use in many connections is particularly well adapted for use in connection with the photographic apparatus constituting the subject matter of my co-pending application Serial No. 341,310, filed February 20, 1929.

What I claim is:—

1. Electrical apparatus for the momentary generation of high power electrical impulses and adapted for operation on alternating current and on direct current, said apparatus comprising in combination an iron core provided with an air gap, a primary and a secondary winding for the core and a wire of high electrical conductivity in series with the primary winding and adapted to be destroyed by the current passing through the primary winding within a predetermined interval after the closing of the circuit of said winding, to open said circuit.

2. Electrical apparatus for the momentary generation of high power electrical impulses and adapted for operation on alternating current and on direct current, said apparatus comprising in combination an iron core provided with an air gap, a primary winding and a secondary winding for said core and means for opening the primary circuit within a predetermined interval after the closing thereof, whereby the total magnetic energy produced by the current flowing in the primary winding is utilized in inducing a current of increased voltage in the secondary winding.

3. Electrical apparatus for the momentary generation of high power electrical impulses and adapted for use on direct current and on alternating current, said apparatus comprising in combination an iron core provided with an air gap, a primary winding and a secondary winding for said core, and means for automatically opening the primary circuit of said apparatus, said last mentioned means on alternating current operation effecting an opening of the primary circuit in predetermined time relation to the current period.

4. Electrical apparatus for the momentary generation of high power electrical impulses and adapted for use on direct current and on alternating current, said apparatus comprising in combination an iron core provided with an air gap, a primary winding and a secondary winding for said core, resistance in said primary winding, a switch for short circuiting said resistance, and a conductor in said primary winding adapted to be destroyed by the current flowing in the primary winding a predetermined interval after the closing of the primary circuit.

5. Electrical apparatus comprising in com-

- bination an iron core provided with an air gap, a primary winding and a secondary winding for said core, a filament of highly refractory material across the secondary winding and adapted to be vaporized by the electric current induced in said secondary winding, resistance in series with the primary winding, a metallic member in series with the primary winding and adapted to be destroyed by the current passing through the primary winding a predetermined interval after the closing of the circuit of the primary winding, and a switch for short circuiting the resistance in the primary winding.
6. Electrical apparatus comprising in combination an iron core provided with an air gap, a primary winding and a secondary winding for said core, a filament of highly refractory material across the secondary winding, a resistance in the circuit of the primary winding, a switch for short circuiting said resistance, a metallic member in the circuit of the primary winding adapted to be destroyed by the current passing through the primary winding a predetermined interval after said resistance has been short circuited, said metallic member opening the circuit of the primary winding, whereby current is induced in the secondary winding and the highly refractory material across the secondary winding vaporized.

This specification signed this 16th day of April, 1929.
